UNITED STATES PATENT OFFICE.

CORNELIUS W. BOGERT, OF BROOKLYN, NEW YORK.

RECEPTACLE.

1,293,317.

Specification of Letters Patent.

Patented Feb. 4, 1919.

Application filed January 24, 1918. Serial No. 213,502.

To all whom it may concern:

Be it known that I, CORNELIUS W. BOGERT, a citizen of the United States, and a resident of the city of New York, borough of Brooklyn, in the county of Kings and State of New York, have invented a new and Improved Receptacle, of which the following is a full, clear, and exact description.

Among the principal objects which the present invention has in view are: to reduce the cost of a receptacle of the character herein after described; to prevent leakage and to strengthen the construction of the receptacle; and to reinforce the structure to avoid collapsing the same.

Drawings.

Figure 1 is a schematic view showing two of the blanks from which the receptacle is constructed when forming a bottle, said blanks being overlaid as when disposed in service relation;

Fig. 2 is a vertical section of a bottle-like receptacle formed from the blanks shown in Fig. 1 constructed and arranged in accordance with the present invention.

Fig. 3 is a vertical section of a receptacle constructed and arranged in accordance with the present invention, the blanks from which it is constructed being shaped to form a straight-sided vessel;

Fig. 4 is a horizontal section, the section being taken as on the line 4—4 in Fig. 3;

Fig. 5 is a horizontal section of a receptacle approximately rectangular in horizontal cross section.

Description.

As seen in the drawings, the blanks 10 and 11 are each shaped to form neck-forming sections 12 and 13. In the sections, the neck-forming ends are connected by strips 14, which are severed at the center and folded back upon the neck-forming sections to reinforce the structure and to form a ridge over which the edge 15 of the inner blank 11 may be folded.

The length of the respective blanks corresponds accurately with the circumference of the receptacle or the laminations of the wall thereof formed by the said blanks when folded over the mold or mandrel. When the blanks are folded over the forms, the edges 16 and 17 are butted to form a closed seam.

When making the bottle form shown in

Fig. 2 of the drawings, the edges 18 of the neck-forming portions are so shaped that when said neck portions are contracted upon the mold, the said edges abut and form closed seams.

When the two blanks 10 and 11 are placed in position to be adhered, they are mutually arranged so that the seams formed by the edges 18 are disposed in staggered relation. This arrangement also insures the necessary 65 staggered relation of the seams formed by the edges 16 and 17 of the blanks.

As the blanks are placed upon the mandrel, a suitable adhesive is disposed between them. The blanks are held on the molds until the adhesive sets, when the mold is withdrawn.

If the shape is one having a contracted mouth or neck end, such as shown in Fig. 2 of the drawings, the mold is preferably withdrawn before the bottom of the receptacle is formed. In all blanks, the bottom of the receptacle is formed from segment-like sections 19 and 20. The sections 19 and 20 converge so that the points 21 thereof are axially alined and superposed.

To avoid leakage which might occur through an aperture left in the receptacle at this point, a disk 22 is inserted between the laminations formed by the sections 19 and 20.

In the manufacture of the receptacles, the adhesive above referred to is distributed on the disk and the sections 19 and 20 are pressed firmly thereupon until the adhesive sets. The disk 22 in this manner effectively closes all seams or openings in the bottom of the receptacle and also reinforces the same.

It will be understood that receptacles constructed and arranged in accordance with the present invention may be formed to a variety of shapes, such as illustrated by Figs. 3 and 5 of the drawings. In Fig. 3, the receptacle has a cylindrical body. It is obvious that if desired, the opening end of the receptacle 100 may be flared without departing from the spirit and scope of the present invention.

In Fig. 5 of the drawings, the receptacle is shown as having a square or substantially rectangular form.

In all instances, whether circular, rectangular, or polylateral, the sections 19 and 20 converge to the center or axis of the receptacle, and the seams formed by the butted edges of the said sections terminate in diver-

gent seams formed by the edges of the nicks 23 in the blanks 10 and 11. Between the nicks 23, a triangular piece 24, which fills in the space between the outer edges of the nicks 5 when the blanks are formed into the completed receptacle. By nicking the blanks in the manner shown, provision is made for distributing the material to permit the turning of the lower edge or perimeter of the bottom 10 of the receptacle.

Suitable covers for the receptacles are formed. These covers are preferably constructed from two layers or laminations adhered in the manner described when referring 15 to the blanks 10 and 11. The covers are shaped or molded to form a raised ridge 25. The ridge 25 forms an annular groove adapted to fit over the opening edge of the receptacle. The edges of the receptacle are 20 formed by overturning the edge 15 of the blanks 11, to form a ridge within the opening edge of the receptacle. In a similar manner the outer blank forming the cover has an inturned edge 26. Preferably the 25 edge 26 of the cover depends sufficiently below the top of the annular space 27 of the cover to extend below the ridge formed by the edge 15. In this manner, a lock is provided for the cover which effectively serves 30 to maintain the same in transit.

Claims.

1. A receptacle as characterized having the body portion thereof formed of laminated sheets permanently attached to one another, each sheet forming one joint substantially lengthwise of said body, the joints of the laminations being relatively staggered and each of said sheets having bottom-forming radially separated sections, said sections converging to the center of the bottom formed thereby; and means disposed between said bottom-forming sections for reinforcing said bottom.
- 45 2. A receptacle as characterized having the body portion thereof formed of laminated sheets permanently attached to one another, each sheet forming one joint substantially lengthwise of said body, the joints 50 of the laminations being relatively staggered, and each of said sheets having bottom-forming radially separated sections, said sections converging to the center of the bottom formed thereby; and means disposed 55 between said bottom-forming sections for reinforcing said bottom and for closing any aperture therethrough.
- 60 3. A receptacle as characterized having the body portion thereof formed of laminated sheets permanently attached to one another, each sheet forming one joint substantially lengthwise of said body, the joints 65 of the laminations being relatively staggered, and each of said sheets having bottom-forming radially separated sections,

said sections converging to the center of the bottom formed thereby; and a disk permanently disposed between the bottom-forming sections of adjacent laminations.

4. A receptacle as characterized having a 70 laminated body, each lamination extending the full circumference of said body and forming a seam extending lengthwise of said receptacle, said laminations having integral bottom-forming radially separated sections, 75 said sections converging to the center of said body; and an insert between the sections of adjacent laminations adhesively secured thereto for reinforcing and closing said bottom.

5. A receptacle as characterized having a laminated body, the laminations each forming one seam extending lengthwise of said body, each lamination having a plurality of neck-forming radially separated sections, 85 said sections converging to form a contracted neck, the adjacent edges of said sections being juxtaposed to form seams, the seams of adjacent laminations being disposed in staggered relation.

6. A receptacle as characterized having a laminated body, the laminations each forming one seam extending lengthwise of said body, each lamination having a plurality of neck-forming radially separated sections, 95 said sections converging to form a contracted neck, the adjacent edges of said sections being juxtaposed to form seams, the seams of adjacent laminations being disposed in staggered relation, the innermost neck-forming sections having end extensions adapted 100 to be rolled outward over the edges of the neck formed by said sections for finishing the end of said neck.

7. A receptacle as characterized having a 105 laminated body, the laminations each forming one seam extending lengthwise of said body, each lamination having a plurality of neck-forming radially separated sections, said sections converging to form a contracted neck, the adjacent edges of said sections being juxtaposed to form seams, the seams of adjacent laminations being disposed in staggered relation, the innermost neck-forming sections having end extensions adapted 110 to be rolled outward over the edges of the neck formed by said sections for finishing the end of said neck; and a plurality of ridge-forming members integrally connected with said neck-forming sections for reinforcing said neck-forming sections for thickening the end of the neck of said receptacle.

8. A receptacle as characterized having a laminated body, the laminations extending 125 completely around the same, each lamination forming one seam extending substantially parallel with the axis of said body, said seams being disposed in relatively staggered relation; a plurality of end-extended 130

radially separated segments integrally connected with said laminations for forming the bottom and neck of said receptacle, the edges of said segments when contracted 5 abutting to form junctions, the seams of each lamination being staggered relatively to the junctions of the adjacent laminations for sealing the openings therebetween; a

finish for the neck of said receptacle, said finish being attached to the inner lamination 10 for extension about the outer lamination; and a reinforcing disk for sealing the bottom of said receptacle, said disk being disposed between the bottom-forming segments of said laminations.

CORNELIUS W. BOGERT.
